SHOE SOLE EDGE TRIMMER

Richard W. Godet, Merrimac, Mass., assignor to
George O. Comeau, Haverhill, Mass.
Filed Jan. 8, 1964, Ser. No. 336,490
17 Claims. (Cl. 12—88)

This invention relates to apparatus for use in trimming the edges of soles, particularly those of the type having one portion, usually the heel area, thicker than the fore part.

It is essential that the edges of shoe soles be trimmed regardless of the material of which they are made and whether or not they are of the type that includes a heel that may either be an integral portion thereof or separately formed and attached thereto in one way or another. While the desired objective is that a sole edge be suitably finished, it is sometimes necessary that the upper surface of a sole be scoured, before use, to ensure that upper structure can be securely bonded thereto. When the sole includes a heel, additional problems exist because, if the edge trimming effect is correct for the fore part of the sole, it may be, depending on the relative thickness of the fore and heel parts, wholly inadequate for properly finishing the edge of the heel part. Conversely, if the edge trimming effect is correct for the heel part of a sole, too much stock may be removed in the trimming of the fore part thereof. Like problems exist when soles of a different thickness are to be edge-trimmed.

The general objective of the invention is to provide edge trimmers for shoe soles that are adapted to meet each of the above generally indicated requirements or combinations thereof and the objective is attained by providing an edge trimmer having a flat support on which a shoe sole is laid with its edge in contact with the peripheries of a rotary trimming member and a rotary guide member. Such trimmers also have a pair of rotatable feed members, one engageable with the under surface of a sole on the support and the other engageable with the upper surface thereof, and these are operable to maintain the edge of the sole against the trimming and guide members. All of the members cooperate to effect the continuous advance and engagement of the edge of the sole with the trimming member throughout its length.

Because of the above referred to variable factors involved in the edge trimming of shoe soles, it is essential to provide adjustments enabling desired trimming effects to be ensured.

A general objective of the invention is, accordingly, the provision in such a sole edge trimmer of means to adjust the relationship between the advance of the edge of the sole and the trimming member to vary the effect of the latter. A specific objective is to accomplish that result by the control of the speed of the guide member and another objective is to accomplish that result automatically whenever the trimming member is in contact with the sole edge in an area where the thickness of the sole is so substantially increased as to otherwise adversely affect the edge trimming.

In an edge trimmer in accordance with the invention, one of the pair of rotatable feed members, typically the upper of them, is movable towards and away from the proximate face of the shoe sole to be trimmed and its upward movement is adjustably opposed. With shoe soles having a thicker heel portion, the heel portion forces the upper feed member upwardly and if it then bore on the sole with increased pressure, the effect of the feed members on the advance of the edge of the sole relative to the trimming member would be varied.

A specific objective of the invention is to accomplish such constant opposition to the upward movement of the

2

upper feed member pneumatically with the delivery conduit to a piston-cylinder unit including a pressure regulator and a further objective is to provide operator controlled means connected to the same unit and operable to so raise the upper feed member as to enable soles to be introduced conveniently and removed from between the feed members.

A further objective of the invention is to utilize the feed member that engages the upper surface of the sole to scour the portions thereof to which upper structure is to be cemented so that the scouring operation can be done simultaneously with the edge trimming operation.

Another objective of the invention is concerned with the trimming member which must, of course, be replaced from time-to-time and which must be capable of being adjustably positioned relative to the other members regardless of its diameter. A specific objective is to accomplish this result by means of a hinged mount for the trimming member and a motor drive therefor, the hinge axis of the mount being vertical and the mount being adjustable as to its angularity, and also transversely.

In the accompanying drawings, there is shown an illustrative embodiment of the invention from which these and other of its objectives, novel features, and advantages will be apparent.

In the drawings:

FIGURE 1 is a partly sectioned and partly broken away side view of a shoe sole edge trimmer in accordance with the invention,

FIGURE 2 is a fragmentary plan view thereof,

FIGURE 3 is a section taken approximately along the indicated lines 3—3 of FIGURE 1,

FIGURE 4 is a fragmentary vertical section on an increased scale taken approximately along the indicated lines 4—4 of FIGURE 2,

FIGURE 5 is a fragmentary, exploded view of the drive for the trimming member,

FIGURE 6 is a fragmentary view, on an increased scale taken approximately along the indicated lines 6—6 of FIGURE 2,

FIGURE 7 is a cross sectioned view of the expandable pulley by which the speed of the feed members is varied, and

FIGURE 8 is a schematic view illustrating the pneumatic circuit in control of the upper of the feed members in relation to the shoe sole.

In the embodiment of the invention illustrated by the drawings, a table is generally indicated at 10 and is shown as having an opening 11, in the front part of its flat, sole-supporting surface 12 and a base 13. At the rear of the table 10, there is an upright 14 for a head 15 spaced above the surface 12 and extending forwardly towards the opening 11.

A shaft 16 is rotatably supported parallel to but below the work supporting table top or surface 12 and a shaft 17 is rotatably supported by an arm 18 pivoted as at 19 to the upright 14. The shafts 16 and 17 have meshing gears 20 and 21 at their rear ends, the teeth of the gear 21 being transversely rounded to enable the arm 18 to be pivoted with the gears 20 and 21 remaining meshed. At their other ends, the shafts 16 and 17 have feed members 22 and 23, the member 22 being shown as a knurled wheel and protruding through the opening 11 for engagement with the undersurface of a sole 24 including a heel 25 and laid tread surface downwardly, on the surface 12, with its edge in contact with the peripheries of both the guide member 26 and the edge trimming member 27. The member 23 is shown as a wire-bristled wheel and it engages the upper surface of the sole 24 with a scouring effect. While the arm 18 may be raised to permit a sole 24 to be placed in position for edge trimming and then removed,

it is connected to the forward end of the head 15 by a vertically slidable stop 28 adjustably threaded into a bracket 29 pivotably connected as at 30 to the arm 18 to limit the approach of the member 23 towards the member 22 when not held apart by a sole 24.

The drive for the members 22 and 23 consists of an electric motor 31 mounted in the base 13 and having a drive pulley 32 connected to the generally indicated pulley 33 of a speed reducer 34 by a belt 35. The driven shaft of the speed reducer 34 is provided with a pulley 36 connected by a belt 37 to a pulley 38 on the shaft 16.

As it is desirable to be able to vary the speed of the feed members 22 and 23, the pulley 33 is shown, see FIGURE 7, as of the type including sections 39 and 40. While both pulley sections are fast on the shaft 41 of the speed reducer 34, the section 40 is slidably splined thereto as at 42, with outward movement being yieldably opposed by a spring 43 backed by a cage 44 fixed on the end of the shaft 41. By increasing the pull of the belt 35 on the pulley 33, the section 40 is moved outwardly against the opposing action of the spring 43 with the result that the effective diameter of the pulley 33 is decreased resulting in an increase in speed at which the shaft 41 is turned by the motor 31. To vary such a pull, and accordingly the speed of the members 22 and 23, the motor 31, see FIGURE 1, is mounted on a bracket 45 pivoted as at 46 to the base structure and pivotably connected as at 47 to a link 48 having a threaded connection 49 with a rotatable stem 50. The stem 50 extends through the front wall 51, where it is provided with a knob 52.

The sole 24 must be securely gripped between the feed members 22 and 23 and, for that reason, downward pressure is applied on the member 23. To accomplish that result, the head 15 is provided with a piston-cylinder unit, the cylinder being indicated at 53 and the stem of its piston at 54. The stem 54 is connected to a bracket 55 pivotally connected as at 56 to the arm 18.

As may be seen in FIGURE 8, a conduit 57 is provided with a valve 58 and an adjustable pressure regulator 59 is connected to the upper end of the cylinder 53 thus to provide predetermined but adjustable opposition to upward movement of the feed member 23 regardless of whether it is in engagement with the fore or thinner part of the sole 24 or in engagement with the heel part 25 thereof. The valve 58 connects a conduit 60 to the conduit 57. The conduit 60 is in communication with a three way valve 61 having a conduit 62 in communication with the lower part of the cylinder 53 so that, when the valve 61 is positioned to connect the conduits 60 and 62, air is delivered to the cylinder 53 under sufficient pressure to raise the arm 18 thus to enable a sole to be inserted or removed from between the members 22 and 23, otherwise the lower end of the cylinder 53 is vented.

It is preferred that the operation of the valve 61 be controlled by the operator by means of a treadle 63 pivoted as at 64 and operatively connected to the valve stem 65 to move it from a normal venting position into its position wherein the arm 18 is raised.

It will be noted that the trimming member 27, which is shown as a cutter, is removably mounted on a vertical shaft 66. In order that the axis of the trimming member 27, regardless of its diameter, may be located in a desired position in or close to a vertical plane inclusive of the axes of the shafts 16 and 17 and in a desired relationship to the feed rolls 22 and 23 and to the guide member 26, the shaft 66 is journaled in a hinge part 67 in the form of a mount connected by the pintle 68 to a hinge part 69 shown as connected to an upright 70 of the base frame by an adjusting screw 71, there being an adjustable screw 72 bearing against the proximate face of the upright 70. By this construction, not only can the mount 67 be shifted transversely but also the axis of the trimming member 27 may be precisely adjusted. For that reason, the front wall 51 of the base 13 is provided with transverse slots 73 for the anchoring screw 74. A set screw 75 is threaded

through the front wall 51 for engagement with the mount 67 to provide means for adjusting its angular relationship relative to the hinge part 69 and the front wall 51. The mount 67 also supports a motor 76 whose pulley 77 is connected to a pulley 78 on the shaft 66 by a belt 79.

The guide member 26 is shown, see FIGURE 2, as mounted on a driven shaft 80 of a speed reducer 81 secured to the work-supporting surface 12 with the axis of the guide member 26 being in a plane in which the feed members 23 and 24 rotate and abutting the opening 11.

The infeed shaft 81A of the speed reducer 81 is shown as connected to a motor 82 by a flexible shaft 83. The motor 82 is provided with a variable speed device, generally indicated at 84, whose adjusting shaft 85 is exposed through the front wall 51 and provided with an adjusting knob 86. A manually operable lock 87 is threaded through the wall 51 and is operable to clamp the segment 88 on the shaft 85 thereagainst. The device 84 is desirably of the type shown in United States Letters Patent No. 2,691,896. With this construction, the operator can quickly and easily adjust the speed of the guide member 26 to secure the desired edge trimming effect with soles of different thickness as well as those of varying thickness.

When it is desired that the speed of the guide member 26 be automatically changed as when the sole is being trimmed in the heel area and that area is materially thicker than in the fore part, the device 84 is provided with an adjustable stop 89, see FIGURE 3, overlying the plate 90 on the shaft 85 and engageable by the rib 91 thereof. A spring 92 is operable to yieldably maintain the rib 91 in a position in which the speed of the guide member 26 is correct for the proper trimming of the fore part of the sole 24. The stop 89 is pre-set to provide, when engaged by the rib 91, that speed of the guide member 26 that results in the movement of the sole 24 relative to the trimming member 27 that provides the desired sole edge trimming in the heel area 25.

The plate 90 is moved against the action of the spring 92 when air is delivered into the cylinder 93 whose piston includes a stem 94 in engagement with the rib 91. An air conduit 95, in communication with the cylinder 93 has a solenoid controlled valve whose circuit 97 includes a switch 98 having an arm 99 disposed as a feeler in contact with the sole 24 and actuated to close the circuit 97 when the heel area 25 is engaged thereby. The switch 98 is mounted on the table top 12 with the feeler arm 99 located closely adjacent the trimming member 26. When the circuit 97 is closed, air is delivered into the cylinder 93 thus to cause the plate 90 to be swung, and accordingly the shaft 85 to be turned to bring the rib 91 against the stop 89 to provide a slower speed of the guide member 26 thereby ensuring an increased trimming effect in the heel area.

If the guide member 26 is enough thinner than a sole 24 in the area of its heel 25, the sole may occasionally be tilted out of position. To prevent such an occurrence, a sole hold-down is used. The hold-down is generally indicated at 100 and may be seen in FIGURES 2 and 6.

The hold-down 100 consists of a base 101 secured to the table top 12 as by a screw 102. The base 101 has side walls 103 supporting the pivot 104 for the rocker arm 105. Forwardly and rearwardly of the pivot axis, the rocker arm 105 is provided with set screws 106 and 107, respectively, adapted to be adjusted to limit the motion of the rocker arm 105. The hold-down arm 108 has a slot 109 enabling it to be adjustably connected to the rocker arm 105 by screws 110. The free end of the arm 108 is U-shaped with its extremity 111 elevated for holding engagement with the heel 25 to prevent its being lifted as a result of its engagement with the guide member 26 and its height is adjustable by means of the set screws 106 and 107.

It will be appreciated that an edge trimmer for shoe soles in accordance with the invention is well adapted to

meet a wide range of requirements. Contributing to this result is the adjustability of speed of both the guide members and the feed members, the adjustability of the opposition to upward movement of the feed member 23, the adjustable hold-down, the adjustability of the axis of the cutting member, and the automatic control of the speed of the feed members.

I claim:

1. In an edge trimmer for shoe soles that are thicker in the heel area than they are forwardly thereof, a flat sole support, a rotatable guide member for advancing a sole edge and a rotatable edge trimming member both rotatably mounted on said support with their axes parallel and with their peripheries engageable by the edge of a sole placed flat on said support, a pair of rotatable feed members, one engageable with the under surface of said sole and the other engageable with the upper surface thereof, means mounting one feed roll for movement towards and away from the sole, said feed members being operable to maintain the edge of the sole against said trimming and guide members as it is advanced by said guide member, all of said members cooperating to effect the continuous advance and engagement of the edge of the sole with said trimming member throughout the entire length, a drive for said feed members, a drive for said trimming member, a drive for said guide member, and means yieldably maintaining predetermined opposition to movement of said movable feed member away from said sole regardless of changes in sole thickness.

2. In an edge trimmer for shoe soles that are thicker in the heel area than they are forwardly thereof, a flat sole support, a rotatable guide member for advancing a sole edge and a rotatable edge trimming member both rotatably mounted on said support with their axes parallel and with their peripheries engageable by the edge of a sole placed flat on said support, a pair of rotatable feed members, one engageable with the under surface of said sole and the other engageable with the upper surface thereof, means mounting one feed roll for movement towards and away from the sole, said feed members being operable to maintain the edge of the sole against said trimming and guide members as it is advanced by said guide member, all of said members cooperating to effect the continuous advance and engagement of the edge of the sole with said trimming member throughout the entire length, a drive for said feed members, a drive for said trimming member, a drive for said guide member, means operable to modify one of said drives to increase the effect of the trimming member on the edge of the sole in the heel area thereof, and means yieldably maintaining predetermined opposition to movement of said movable feed member away from said sole regardless of changes in sole thickness.

3. In an edge trimmer for shoe soles that are thicker in the heel area than they are forwardly thereof, a flat sole support, a rotatable guide member for advancing a sole edge and a rotatable edge trimming member both rotatably mounted on said support with their axes parallel and with their peripheries engageable by the edge of a sole placed flat on said support, a pair of rotatable feed members, one engageable with the tread surface of said sole and the other engageable with the upper surface and being a scouring member, means mounting one feed roll for movement towards and away from the sole, said feed members being operable to maintain the edge of the sole against said trimming and guide members as it is advanced by said guide member, all of said members cooperating to effect the continuous advance and engagement of the edge of the sole with said trimming member throughout the entire length, a drive for said feed members, a drive for said trimming member, a drive for said guide member, and means yieldably maintaining predetermined opposition to movement of said movable feed member away from said sole regardless of changes in sole thickness.

4. In an edge trimmer for shoe soles that are thicker in the heel area than they are forwardly thereof, a flat sole support, a rotatable guide member for advancing a sole edge and a rotatable edge trimming member both rotatably mounted on said support with their axes parallel and with their peripheries engageable by the edge of a sole placed flat on said support, a pair of rotatable feed members, one engageable with the under surface of said sole and the other engageable with the upper surface thereof, means mounting one feed roll for movement towards and away from the sole, said feed members being operable to maintain the edge of the sole against said trimming and guide members as it is advanced by said guide member, all of said members cooperating to effect the continuous advance and engagement of the edge of the sole with said trimming member throughout the entire length, a drive for said feed members, a drive for said trimming member, a drive for said guide member, and pneumatic means including a piston-cylinder unit and a supply conduit in communication therewith provided with a pressure regulator, said means yieldably maintaining predetermined opposition to movement of said movable feed member away from the other feed member regardless of changes in sole thickness.

5. In an edge trimmer for shoe soles that are thicker in the heel area than they are forwardly thereof, a flat sole support, a rotatable guide member for advancing a sole edge and a rotatable edge trimming member both rotatably mounted on said support with their axes parallel and with their peripheries engageable by the edge of a sole placed flat on said support, a pair of rotatable feed members, one engageable with the under surface of said sole and the other engageable with the upper surface thereof, means mounting one feed roll for movement towards and away from the sole, said feed members being operable to maintain the edge of the sole against said trimming and guide members as it is advanced by said guide member, all of said members cooperating to effect the continuous advance and engagement of the edge of the sole with said trimming member throughout the entire length, a drive for said feed members, a drive for said trimming member, a drive for said guide member, pneumatic means including a piston-cylinder unit connected to said movable feed member and a supply conduit in communication therewith and provided with a pressure regulator, said means yieldably maintaining predetermined opposition to movement of said movable feed member regardless of changes in sole thickness, and an operator actuated pneumatic control in communication with said unit and operable to raise said movable member out of contact with said sole.

6. In an edge trimmer for shoe soles that are thicker in the heel area than they are forwardly thereof, a flat sole support, a rotatable guide member for advancing a sole edge and a rotatable edge trimming member both rotatably mounted on said support with their axes parallel and with their peripheries engageable by the edge of a sole placed flat on said support, a pair of rotatable feed members, one engageable with the under surface of said sole and the other engageable with the upper surface thereof, means mounting one feed roll for movement towards and away from the sole, said feed members being operable to maintain the edge of the sole against said trimming and guide members as it is advanced by said guide member, all of said members cooperating to effect the continuous advance and engagement of the edge of the sole with said trimming member throughout the entire length, a drive for said feed members, a drive for said trimming member, a drive for said guide member, and means operable to adjust the drive for said guide member to vary the speed thereof to vary the effect of the trimming member on the edge of the sole in the heel area thereof, and means yieldably maintaining predetermined opposition to movement of said movable feed member away from said sole regardless of changes in sole thickness.

7. In an edge trimmer for shoe soles that are thicker in the heel area than they are forwardly thereof, a flat sole support, a rotatable guide member for advancing a sole edge and a rotatable edge trimming member both rotatably mounted on said support with their axes parallel and with their peripheries engageable by the edge of a sole placed flat on said support, a pair of rotatable feed members, one engageable with the under surface of said sole and the other engageable with the upper surface thereof, means mounting one feed member for movement towards and away from the sole said feed members being operable to maintain the edge of the sole against said trimming and guide members as it is advanced by said guide member, all of said members cooperating to effect the continuous advance and engagement of the edge of the sole with said trimming member throughout the entire length, a drive for said feed members, a drive for said trimming member, a drive for said guide member, a feeler engageable with the upper face of a sole disposed on said support and movable in response to changes in its thickness, and means operable by feeler movement to modify one of said drives to increase the effect of the trimming member on the edge of the sole in the heel area thereof.

8. In an edge trimmer for shoe soles that are thicker in the heel area than they are forwardly thereof, a flat sole support, a rotatable guide member for advancing a sole edge and a rotatable edge trimming member both rotatably mounted on said support with their axes parallel and with their peripheries engageable by the edge of a sole placed flat on said support, a pair of rotatable feed members, one engageable with the under surface of said sole and the other engageable with the upper surface thereof, means mounting one feed member for movement towards and away from the sole said feed members being operable to maintain the edge of the sole against said trimming and guide members as it is advanced by said guide member, all of said members cooperating to effect the continuous advance and engagement of the edge of the sole with said trimming member throughout the entire length, a drive for said feed members, a drive for said trimming member, a drive for said guide member, a feeler engageable with the upper face of a sole disposed on said support and movable in response to changes in its thickness, and means operable by feeler movement to modify said guide member drive to increase the effect of the trimming member on the edge of the sole in the heel area thereof.

9. In an edge trimmer for shoe soles that are thicker in the heel area than they are forwardly thereof, a flat sole support, a rotatable guide member for advancing a sole edge and a rotatable edge trimming member both rotatably mounted on said support with their axes parallel and with their peripheries engageable by the edge of a sole placed flat on said support, a pair of rotatable feed members, one engageable with the under surface of said sole and the other engageable with the upper surface thereof, means mounting one feed member for movement towards and away from the sole, said feed members being operable to maintain the edge of the sole against said trimming and guide members as it is advanced by said guide member, all of said members cooperating to effect the continuous advance and engagement of the edge of the sole with said trimming member throughout its entire length, a drive for said feed member, a drive for said trimming member, a two speed drive for said guide member, a feeler engageable with the upper face of a sole disposed on said support and movable in response to changes in its thickness, and means operable by feeler movement to control said guide member drive to establish the low speed thereof in the thicker area and the high speed thereof in the thinner area.

10. In an edge trimmer for shoe soles that are thicker in the heel area than they are forwardly thereof, a flat sole support, a rotatable guide member for advancing a sole edge and a rotatable edge trimming member both rotatably mounted on said support with their axes parallel

and with their peripheries engageable by the edge of a sole placed flat on said support, a pair of rotatable feed members, one engageable with the under surface of said sole and the other with the upper surface thereof, means mounting one feed member for movement towards and away from the sole said feed members being operable to maintain the edge of the sole against said trimming and guide members as it is advanced by said guide member, all of said members cooperating to effect the continuous advance and engagement of the edge of the sole with said trimming member throughout its entire length, a drive for said feed member, a drive for said trimming member, a drive for said guide member including a motor and a speed changer driven thereby and including a control, a spring yieldably holding said control in a position providing high speed, a feeler engageable with the upper face of a sole disposed on said support and movable into an operative position by the heel area, and a normally open switch closed by the feeler in its operative position, and means to move said control into a low speed position, said means including an operating circuit including said switch.

11. The edge trimmer of claim 9 in which the circuit includes a solenoid, and the control moving means includes an air operated piston and a valve in control thereof and opened by the solenoid when energized.

12. The edge trimmer of claim 9 in which the control includes a speed controlling arm to which the spring and the moving means are both connected and an adjustable stop is provided to stop the arm when actuated by the moving means.

13. In an edge trimmer for shoe soles that are thicker in the heel area than they are forwardly thereof, a flat sole support, a rotatable guide member for advancing a sole edge and a rotatable edge trimming member both rotatably mounted on said support with their axes parallel and with their peripheries engageable by the edge of a sole placed flat on said support, a pair of rotatable feed members, one engageable with the under surface of said sole and the other engageable with the upper surface thereof, means mounting one feed member for movement towards and away from the sole said feed members being operable to maintain the edge of the sole against said trimming and guide members as it is advanced by said guide member, all of said members cooperating to effect the continuous advance and engagement of the edge of the sole with said trimming member throughout the entire length, a drive for said feed members, a drive for said trimming member, a drive for said guide member, and means to adjust universally the pivot of the axis of the trimming member.

14. In an edge trimmer for shoe soles that are thicker in the heel area than they are forwardly thereof, a flat sole support, a rotatable guide member for advancing a sole edge and a rotatable edge trimming member both rotatably mounted on said support with their axes parallel and with their peripheries engageable by the edge of a sole placed flat on said support, a pair of rotatable feed members, one engageable with the under surface of said sole and the other engageable with the upper surface thereof, means mounting one feed member for movement towards and away from the sole said feed members being operable to maintain the edge of the sole against said trimming and guide members as it is advanced by said guide member, all of said members cooperating to effect the continuous advance and engagement of the edge of the sole with said trimming member throughout the entire length, a drive for said feed members, a drive for said trimming member, a drive for said guide member, and mounting means for said drive for said trimming member including a hinge part in the form of a mount, a part adjustably attached to said trimmer for transverse movement, the hinge axis being vertical, said mount including means for adjusting its angular relation to said attached hinge part, said mounting means enabling the axis

of said trimming member to be set in a desired relation to the feed members.

15. In an edge trimmer for shoe soles that are thicker in the heel area than they are forwardly thereof, a flat sole support, a rotatable guide member for advancing a sole edge and a rotatable edge trimming member both rotatably mounted on said support with their axes parallel and with their peripheries engageable by the edge of a sole placed flat on said support, a pair of rotatable feed members, one engageable with the under surface of said sole and the other engageable with the upper surface thereof, means mounting one feed member for movement towards and away from the sole said feed members being operable to maintain the edge of the sole against said trimming and guide members as it is advanced by said guide member, all of said members cooperating to effect the continuous advance and engagement of the edge of the sole with said trimming member throughout the entire length, a drive for said feed members, a drive for said trimming member, a drive for said guide member and a

vertically adjustable hold-down on said supports including an end portion overlying the sole close to the upper of said feed rolls.

16. The edge trimmer of claim 15 in which the hold down has a pivoted connection with the support.

17. The edge trimmer of claim 15 in which the hold down includes a first portion, a base fixed on the support to which the first portion is pivotally connected, and a second portion connected to the first portion to enable the length of the hold down to be varied.
